(57) **CLAIM**

I claim the ornamental design for a portable electronic device holder, as shown and described.

DESCRIPTION

FIG. 1 is a perspective view of a portable electronic device holder, showing my new design as used;

FIG. 2 is a perspective view thereof;

FIG. 3 is a rear elevational view thereof;

FIG. 4 is a front elevational view thereof;

FIG. 5 is a left-side elevational view thereof;

FIG. 6 is a right-side elevational view thereof;

FIG. 7 is a top plan view thereof; and,

FIG. 8 is a bottom plan view thereof.

The broken line showing of environment in the drawings is for illustrative purposes only and forms no part of the claimed design.
